CLAIM

The ornamental design for a golf club head, as shown and
described.

DESCRIPTION

FIG. 1 is a top perspective view of a golf club head
according to a first embodiment;
FIG. 2 is a bottom perspective view of the golf club head of
FIG. 1;
FIG. 3 is a front elevational view of the golf club head of
FIG. 1;

FIG. 4 is a rear elevational view of the golf club head of FIG.
1;
FIG. 5 is a top view of the golf club head of FIG. 1;
FIG. 6 is a bottom view of the golf club head of FIG. 1;
FIG. 7 is a left side view of the golf club head of FIG. 1;
FIG. 8 is a right side view of the golf club head of FIG. 1;
FIG. 9 is a top perspective view of a golf club head
according to a second embodiment;
FIG. 10 is a bottom perspective view of the golf club head of
FIG. 9;
FIG. 11 is a front elevational view of the golf club head of
FIG. 9;
FIG. 12 is a rear elevational view of the golf club head of
FIG. 9;
FIG. 13 is a top view of the golf club head of FIG. 9;
FIG. 14 is a bottom view of the golf club head of FIG. 9;
FIG. 15 is a left side view of the golf club head of FIG. 9;
FIG. 16 is a right side view of the golf club head of FIG. 9;
FIG. 17 is a top perspective view of a golf club head
according to a third embodiment;
FIG. 18 is a bottom perspective view of the golf club head of
FIG. 17;
FIG. 19 is a front elevational view of the golf club head of
FIG. 17;
FIG. 20 is a rear elevational view of the golf club head of
FIG. 17;
FIG. 21 is a top view of the golf club head of FIG. 17;
FIG. 22 is a bottom view of the golf club head of FIG. 17;
FIG. 23 is a left side view of the golf club head of FIG. 17;
and,
FIG. 24 is a right side view of the golf club head of FIG. 17.
The broken lines shown on the drawings form no part of the
claimed design.
